The broken lines shown in the drawings illustrate portions of the cartridge component that form no part of the claimed design.

In FIGS. 1-30, solid lines with a lighter line weight are used to illustrate the approximate three-dimensional nature of the claimed design and provide better understanding as to the contours of the claimed design. It is to be understood that such lighter-weight solid lines are not surface decoration or part of the ornamental design, but are merely provided as a visual aid to allow better understanding of the contours in the ornamental design.

The attached Appendix includes additional information relating to the claimed design, including drawings.
